UNITED STATES PATENT OFFICE.

JOSEPH NOVIN, OF NEW YORK, N. Y., ASSIGNOR TO THE CENTRE LIGHTING FIXTURE MFG. CO., OF NEW YORK, N. Y., A PARTNERSHIP CONSISTING OF JOSEPH NOVIN AND SAMUEL RIBAK.

DESIGN FOR A LIGHTING-FIXTURE BRACE OR ARTICLE OF ANALOGOUS NATURE.

Application filed February 9, 1929. Serial No. 29,985. Term of patent 3½ years.

To all whom it may concern:

Be it known that I, JOSEPH NOVIN, of the city of New York, county of Bronx, and State of New York, have invented a new, original, and ornamental Design for a Lighting-Fixture Brace or Article of Analogous Nature, of which the following is a specification, reference being had to the accompanying drawing, forming a part hereof.

In the drawing:

Figure 1 is a side elevational view of the lighting fixture brace or article of analogous nature; and

Figure 2 is a diagrammatic edge view in outline.

A dominating feature of the design resides in the employment of columns A of marble or like appearing material which contrasts with the metal employed in the remainder of the article.

I claim:

The ornamental design for a lighting fixture brace or article of analogous nature substantially as shown and described.

JOSEPH NOVIN.
